UNITED STATES PATENT OFFICE.

PRESTON M. BRUNER, OF ST. LOUIS, MISSOURI.

FLOOR CONSTRUCTION.

SPECIFICATION forming part of Letters Patent No. 530,744, dated December 11, 1894.

Application filed October 1, 1894. Serial No. 524,629. (No model.)

To all whom it may concern:

Be it known that I, PRESTON M. BRUNER, a citizen of the United States, residing at the city of St. Louis, State of Missouri, have invented a certain new and useful Improvement in Floor Constructions, of which the following is a full, clear, and exact description, reference being had to the accompanying drawings, forming part of this specification, 55 wherein—

Figure 1 represents a perspective view of the manner of practicing my invention, and Fig. 2 is a modification.

This invention relates to a new and useful improvement in the manner of constructing floors of artificial stone, and consists, generally stated, in arranging upon the I-beams, suitable caps, which are formed with flanges, to which flanges are connected sheets of metal 15 whose ends terminate against the I-beams. The material forming the floor is then laid upon the sheets of metal so supported, and in and around the depending portions of the caps, so that the whole forms, when completed, a permanent floor, which is rigidly supported in place and which will sustain a great weight.

Heretofore, the manner of constructing floors of this character when the ceiling has 20 been made, has been to build in the bays or space between two I-beams, a substructure upon which the composition material is laid. After the material has become set, the substructure is removed. In following this practice, the one great objection is the enormous weight of the floor itself; also, in practicing this method, when the ceiling has been made, it is impossible to remove the substructure from that section of the bay which is last finished.

In this invention, I form a permanent substructure upon which the composition material is laid and which substructure forms part of the finished floor.

In the drawings, 1 indicates the I-beams. Upon the upper flanges of these I-beams, are placed caps 2, which, as shown to the left of Fig. 1, may be formed of strips of material of a suitable width and bent in the manner suitable to attach the substructure, or, as shown in the middle of the figure, said cap may be made continuous, the depending flanges of which are perforated, as at 2^a, to permit the material to be forced behind the same, or, as 45 shown in the right of the figure, the cap may be made continuous and the flanges formed as teeth, which are swaged to permit the material to be introduced behind the same. In whatever manner the caps may be formed, they are provided with flanges 2^b, to which 50 are attached the sheets forming the permanent substructure by rivets or in any suitable manner.

The sheets or webs forming the permanent substructure are provided with some means 55 whereby the material, when laid thereon, will become so associated with the sheet as to be inseparable therefrom. The sheet numbered 3 in the drawings has a tongue or bridge punched up, under which the material may 60 be received when being laid. The sheet 4 has a series of upwardly-projecting pins which extend up into the material, to offer an adhering surface. Sheet 5 has secured thereto a series of T-beams. Sheet 6 is shown as being provided with a number of I-beams; 65 sheet 7, with a number of L-shaped beams; the beams in all of said sheets—5, 6, and 7—being preferably arranged parallel to each other and to the supporting-beam 1, so that 70 80 they will not interfere with the sagging of the sheet, forming the permanent substructure. Sheet 8 is formed with a series of corrugations, and sheet 9 is formed with a series of folds. 75

I have shown many forms of the different ways in which the sheets or webs may be made or provided with means whereby the material, when laid, will become permanently attached to its supporting sheet or web. The 85 object in so intimately connecting the composition material to its supporting sheet throughout the entire surface of said sheet, is to take advantage of a well-known principle that two bodies intimately connected or attached to each other will sustain four times the weight that either of them alone would sustain; for illustration, two boards laid flat, side by side, will deflect but one-half of what would be the deflection of one of the 90 boards under a given weight. Two boards, laid one upon another, will deflect but one-half the distance of a single board under a given weight, while two boards intimately connected to each other throughout their 95 length will have a deflection equal to one-fourth of the deflection of a single board under a given weight. Another object in so

intimately connecting the composition material to its permanent support is to distribute its weight evenly over the entire area of the floor, thereby obviating the tendency of the 5 floor to pull the I-beams 1 together at their tops.

The sheets forming the permanent sub-structure, are preferably formed with a sag in their middle, which gives to the finished 10 floor a bellied appearance on its under side, making the bulk of the material the greatest at the middle of the bay, where it is least sup-ported, or farthest from the point of support.

At 10, I have shown the permanent sub-15 structure as being formed with depending flanges, which rest upon the lower flanges of the I-beams 1. In this construction, it will be noticed that the substructure is not only supported by the caps 2, but is likewise sup-20 ported by the I-beams, and, between the flanges 10 and the I-beams, are afforded spaces into which may be introduced the compo-25 sition material forming the floor, which compo-sition material, when set, will preserve the I-beam webs, and at the same time provide an additional support at the edges of the span.

In this application, I have not shown any particular form of ceiling, which can be used with my invention, as there are forms in ex-30 istence which will answer the purpose admirably—such, for instance, as that shown in United States Letters-Patent No. 356,703, of January 25, 1887, and No. 469,121, of February 16, 1892. However, I do not wish to limit my-35 self to any particular form of ceiling.

In Fig. 2, I have shown a slight modification of the manner of attaching the caps to the supporting beams. In this figure, the caps are formed directly on the web or sheet and 40 extend over the I-beams to which they may be riveted, or they may be riveted to each other.

In constructing the floor where the caps are integral with the sheets or webs, the same are 45 preferably perforated along the vertical walls, and the channels of the supporting beams, having been previously walled up with compo-50 sition material, as shown at 11. When the composition material is laid upon the sheet or webs forming the substructure, said material will be forced through the openings in the vertical wall of the caps against the wall 11, and, when the material sets, the material filling the openings will prevent lateral move-55 ment, which is essential to the strength of the flooring. It is, also, essential that the sheet or web, which, I might add, could be in the form of the woven web, as well as a pressed web, as shown at No. 3, should maintain in a 60 positive relation to the material composing the floor proper, as any slipping or play between these parts will considerably weaken the structure.

Having thus described my invention, what 65 I claim, and desire to secure by Letters Patent, is—

1. The combination with supporting beams,

of sheet metal or webbing which is supported from the tops of said beams, said metal or webbing spanning the bay and being so formed 70 that the material which is laid thereon to form the floor, comes in contact with the supporting beams to prevent a swinging or lateral movement, substantially as described.

2. The combination with supporting beams, 75 of sheet metal or webbing which is supported from the tops of said beams, and which bridges the bay, said supporting beams having their channels filled in with composition material 80 between the webs of the beams and depend-ing portions of the caps, whereby lateral move-85 ment of the middle portion of the span is pre-vented, substantially as described.

3. The combination with supporting beams, 85 of caps which are provided with depending flanges, which flanges are formed with open-90 ings through which may be introduced the material composing the floor proper, and a permanent substructure, which is secured to the flanges of said cap, substantially as de-scribed.

4. The combination with supporting beams, 95 of caps which straddle the same, depending flanges extending from said caps, said flanges being so formed as to afford means of attach-100 ment for the substructure and to permit the material to be forced behind the flanges, and sheet metal which bridges the bay and is per-manently secured to said caps, substantially as described.

5. The combination with supporting beams, 105 of caps, and sheet metal or webbing which is secured to the caps and bridges the bay, said sheet metal or webbing being bellied or sagged at its middle portion, and having means for 110 affording an intimate attachment of the compo-sition material thereto, substantially as de-scribed.

6. A floor which is composed of sheet metal 110 or webbing, and composition material, said metal being continuous the length of the bay and sagged between its points of support so as to continuously increase the bulk of mate-115 rial midway the bay, substantially as de-scribed.

7. The combination with the supports, of 120 caps straddling the same, sheet metal or webbing which is secured to said caps, and which metal bridges the bay, means on the sheet metal or webbing for affording intimate at-125 tachment therebetween and the composition material which is laid thereon, said sheet being sagged at its middle, so that when the ma-terial forming the floor proper is leveled, its greatest thickness will be at the middle of the span, substantially as described.

In testimony whereof I hereunto affix my signature, in presence of two witnesses, this 20th day of September, 1894.

PRESTON M. BRUNER.
